NOVELTY GLOVE

Joan O'Brien, Los Angeles, Calif.

Application September 19, 1955, Serial No. 37,994

Term of patent 14 years

(Cl. D3—11)

Fig. 1

Fig. 2

Fig. 3

Fig. 4

Fig. 1 is a rear view of a novelty glove showing my new design;

Fig. 2 is a side view thereof;

Fig. 3 is a front view; and

Fig. 4 is a rear perspective view thereof as it appears in partially clenched position.

I claim:

The ornamental design for a novelty glove, substantially as shown and described.
